UNITED STATES PATENT OFFICE.

WILLIAM HENRY LINDSAY, OF BRISTOL, ENGLAND.

COIL CLUTCH AND BRAKE.

SPECIFICATION forming part of Letters Patent No. 577,961, dated March 2, 1897.

Application filed May 7, 1896. Serial No. 590,531. (No model.)

To all whom it may concern:

Be it known that I, WILLIAM HENRY LINDSAY, a subject of the Queen of Great Britain and Ireland, residing at Bristol, England, have invented an Improved Coil Clutch and Brake and Reversing-Gear for Winding and Hauling Engines, in part applicable to clutch-pulleys and shaft-couplings, of which the following is a specification.

This invention consists in an improved coil clutch and brake for winding and hauling engines and in reversing-gear for the same. The coil is also applicable to clutch-pulleys and to coupling-shafts.

As arranged as a clutch for a winding and hauling engine and to serve also as a brake therefor, a coil of steel or other suitable metal is wrapped around the winding-drum shaft or a bush keyed thereon. The coil preferably tapers in opposite directions from a central head which engages in a recess provided for it in a saddle secured to the drum, thus making it a double drive-coil. The coil is carried on the drum, and when desired is made to bind upon the bush or boss by moving in the proper direction a sleeve loosely carried on the drum-shaft and arranged to act through levers upon the tails of the coil. Reverse movement of the sleeve causes the coil to unbind. The coil acts as a clutch in winding and as a brake in lowering without necessitating reversing of the drum-shaft.

Reversing-gear in which coils are employed is applied, and the drum is thereby adapted to raise and lower on either hand, as may be required, without necessitating reversing the engine.

In the accompanying drawings, Figure 1 represents, partly in elevation and partly in section, my coil clutch and brake as applied to the drum of a winding and hauling engine and the combination therewith of reversing-gear by means of which the drum is adapted to raise and lower on either hand. Fig. 2 is an under side plan as seen from below the winding-drum. Fig. 3 is a section on the line xx in Fig. 1 and shows a part of the coil. Fig. 4 is a side view, and Fig. 5 an end view on line yy , Fig. 4, looking to the left, showing the revolving parts. The remaining figures show modifications. Fig. 6 is a side view, partly in central vertical section, show-

ing one-half of the double coil and the adjacent parts; and Fig. 7 is an end view of the principal parts thereof. Fig. 8 is a side view, 55 partly in section; Fig. 9, a section quartering thereto; Fig. 10, a section on the line zz in Fig. 9, looking to the left; and Fig. 11 is a section corresponding to Fig. 9, but with parts formed integral therewith which allow 60 the device to serve also as a pulley.

Similar letters of reference indicate corresponding parts in all the figures where they appear.

The coil b , which consists of one piece of 65 steel or other suitable metal throughout, surrounds a bush c , keyed on the shaft d of the winding-drum a . The coil b tapers from a central head b' in opposite directions and has, therefore, two small ends or tails b^2 . 70

Referring to Figs. 1, 2, and 3, the head b' engages in a recess provided for it in a saddle e , bolted or otherwise secured to the drum a . A lever f , pivoted in a bracket f' , bolted to the drum, acts through the screws f^2 upon 75 the two tails b^2 of the coil b , in which tails the screws bear. The screws f^2 are for equalizing the action and for taking up slack in the coil due to wear or other cause. An arm g is connected at one end to the lever f and 80 toward the other end to a rod h , connected to a sleeve i , loose on the drum-shaft d , on which the sleeve i is free to be moved axially by means of the rocking shaft i' . Movement of the sleeve i toward the drum a causes the 85 coil b , acted upon at the tails by the lever f through the screws f^2 , to contract throughout its whole length on the bush c , which, prior to being thus bound, rotates within the coil b . Binding of the coil b on the bush c causes 90 the drum a , previously stationary, to rotate with the shaft d .

By moving the sleeve i outward on the shaft d —that is to say, away from the drum—the coil b is released to a degree which is under control, and hence the coil serves as a 95 brake governing the drum a in lowering or unwinding.

The lever f may be fitted with buffer-springs for cushioning the effect of putting the coil 100 into and out of binding action.

It will be observed that the construction relieves the mechanism of any tendency to either tighten or relax the grip of the coil

upon the shaft or bush. The double coil arranged according to my invention will always apply at each end or tail of the coil with equal force and will relax the grip at each equally, 5 because the tendency of the motion to tighten the grip on one end or tail of my coil is exactly offset by the tendency of the motion to induce the opposite effect on the opposite end or tail. The adjusting-screws f^2 allow imperfect workmanship and unequal wear to be compensated for with great nicety.

The reversing-gear, which enables the drum a to raise and lower on either hand without reversing the driving-shaft of the engine, 15 consists of a train of bevel-wheels k k' k^2 , of which k' is free to rotate on a spindle in a pedestal l . The wheel k is keyed upon the driving-shaft d' , which extends into the hub m . The wheel k^2 is loose on the drum-shaft d . Between the wheels k and k^2 is a sleeve n , loosely carried on the shaft d and free to be moved axially through the medium of the hand-lever n , pivoted in a lug n^2 , provided on the pedestal l . Keyed on the driven shaft d , which is 25 capable of being driven in reverse directions, is a bush o , around which is wrapped a steel coil p , which is bolted at the head to the wheel k . On the tail of the coil bears an adjustable screw s , carried by a lever q , pivoted in 30 a bracket r , bolted to the wheel k . Similarly a coil p' is wrapped around a bush o' , keyed on the shaft d . The coil p' is connected at the head to the wheel k^2 and on the tail bears an adjustable screw s' , carried by a lever q' , 35 pivoted in a bracket r' , bolted to the wheel k^2 . When the sleeve n is in the position shown at Fig. 1, the wheels k k' are rotated by the driving-shaft d' and the wheel k^2 is rotated by the wheel k' . The bushes o and o' are stationary within the coils p p' , which 40 revolve around them. When the sleeve n is brought into contact with the lever q , the coil p binds on the bush o and the winding-drum shaft d and drum a rotate in the same direction as the driving-shaft d' . When it is required to drive the drum-shaft d in the reverse direction, the sleeve n is withdrawn from contact with the lever q and put into contact with the lever q' . The coil p' then 45 binds on the bush o' and the motion of the drum-shaft d is reversed.

Reversing may be effected without jar or shock, and, when desirable, the drum may be moved more slowly than the shaft by permitting the bushes to slip within the coils by 55 regulating the pressure on the levers q or q' , as the case may be, or by correspondingly varying the force applied to the rocking shaft i , and consequently to the levers f .

60 I use the term "drum" to indicate any part which is to be driven and released, as required. As shown, the drum is adapted for rotating the shaft and also for winding on its periphery a rope or chain to serve in a hoisting or releasing engine.

A bush need not necessarily be employed, as in some cases the coil or coils may, both as

regards the drum and the reversing-gear, be wrapped directly around the shaft.

In Figs. 6 and 7 is illustrated means for 70 putting the coil b into and out of action through a rack i^2 , secured to the sleeve i and carried in a bracket fixed to the shell a . The rack i^2 gears with the pinion i^3 , which is centered in the said bracket and has an internal 75 female screw-thread, which engages with the male-threaded screw i^4 . When by the action of the sleeve i the screw i^2 is affected, it travels horizontally, being prevented from rotating by the pins i^5 taking into the groove longitudinally cut in it. The adjustable screw i^2 for taking up the wear of the coil is passed through the coil-tail.

Fig. 8 and succeeding figures illustrate the application of the double drive-coil b to a 80 shaft-coupling. The coil b is wrapped around the hollow boss c , keyed on the driving-shaft d . Pivoted to the shell t is the lever q , against which bear the adjustable screws f^2 , screwed through the coil-tails b^2 . The coil-head b' is 90 held to the shell t and is kept in place by the gun-metal strap u . The coil is caused to bind on the boss c , previously rotating freely within the coil, by moving the sleeve i into contact with the lever q . The shell t then 95 rotates and carries with it the separate shaft d' , to which it is keyed. When the sleeve i is moved away from the lever q , the coil unbinds, and the shell t no longer rotates. A spring s^* assists to return the lever q to its 100 normal position. q^3 is a stop to limit the range of movement of the lever q .

At Fig. 11 is illustrated the application of the double drive-coil to a pulley v . The lever q is of the same kind as shown in Figs. 105 8, 9, and 10, and the coil b , which is held at the head b' to the pulley-shell t and kept in place by the gun-metal strap u , is actuated to bind on the boss c or unbind therefrom by moving the rocking shaft i' and sleeve i in 110 the proper direction. The lever q , which through the adjusting-screws f^2 acts on the tails of the coil, is pivoted to the shell t and is turned on its pivot by the sleeve i .

115 Springs may be arranged to hold the coil in or out of bind, as may be required.

Instead of using one coil, such as b , two coils may be employed, each tapering from a head to a tail, the heads being secured together midway along the bush c , or the coil-tails may meet midway in the bush, the heads 120 being outward.

The coil is not necessarily tapered. In cases where the loads are heavy and driving is fast the coil is preferably of uniform section throughout.

I claim as my invention—

1. In mechanism of the class described, a rotary shaft and a drum mounted loosely thereon, in combination with a spring-coil surrounding the shaft and centrally secured to the drum, and provisions connected with the ends of the coil and operable from the outside for torsionally moving said ends to tighten

- the grip of such coil, all arranged for joint operation substantially as herein specified.
2. In mechanism of the class described, a rotary shaft and a drum mounted loosely thereon, in combination with a double spring-coil surrounding the shaft in opposite directions, arranged as shown so that the tendency of one part of the coil to tighten shall be offset by the tendency of the other part of the coil to become relaxed by the friction, and with provisions connected with the ends of the coil for tightening and relaxing the grip of such coil at will, substantially as herein specified.
- 15 3. In mechanism of the class described, a rotary shaft and a drum mounted loosely thereon, in combination with a double spring-coil surrounding the shaft, arranged as shown, so that the tendency of one part of the coil to tighten shall be offset by the tendency of the other part of the coil to become relaxed by the friction, and with a lever f turning on a center revolved with the drum and connected with the ends of the coil and having an arm g , and the rod h and its connections for tightening and slackening the grip of both parts of such double coil, all arranged for joint operation substantially as herein specified.
- 20 4. In mechanism of the class described, a shaft and a drum mounted loosely thereon, in combination with a double spring-coil surrounding the shaft, arranged as shown so that the tendency of one part of the coil to tighten shall be offset by the tendency of the other part of the coil to become relaxed by the friction, and with a lever f turning on a center revolved with the drum and connected with the ends of the coil and having an arm g as
- 25 shown, and the rod h and its connections for tightening and relaxing the grip of both parts of such double coil, and with adjusting-screws f^2 to adjust the connection of the lever to the two parts of the coil independently, all arranged for joint operation substantially as herein specified.
- 40 5. In mechanism of the class described, a rotary shaft and a drum mounted loosely thereon, in combination with a spring-coil centrally secured to the part to be driven and surrounding the shaft, and provisions operable from the outside for torsionally moving the ends of the spring to tighten and relax the grip of the same, and with a separate coupling and controlling means n for connecting and disconnecting the shaft, all arranged for joint operation substantially as herein specified.
- 45 6. In mechanism of the class described, a rotary shaft and a drum mounted loosely thereon, in combination with a spring-coil surrounding the shaft, and provisions operable from the outside for tightening and relaxing the grip of such coil, and with a separate coupling and controlling means n for connecting and disconnecting the shaft and with the 50 gear-wheels k , k' , k^2 , for allowing the relative motions of the two parts d , d' , of the shaft to be reversed at will, all arranged for joint operation substantially as herein specified.
- 55 In testimony whereof I have signed my 70 name to this specification in the presence of two subscribing witnesses.
